United States Patent Office

Des. 182,707
Patented May 6, 1958

182,707

SHOE

John A. Borden, South Miami, Fla.

Application April 23, 1957, Serial No. 45,865

Term of patent 14 years

(Cl. D7—7)

Fig. 1.

Fig. 3.

Fig. 2.

Fig. 2 is a perspective view of the side opposite that shown in Fig. 1; and

Fig. 3 is a plan view of the shoe with the tongue portion folded forwardly.

I claim:

The ornamental design for a shoe, as shown.
